UNITED STATES PATENT OFFICE.

BENJAMIN F. FOSS, OF FAIRFIELD, MAINE.

RATCHET SCREW-DRIVER.

No. 873,363.

Specification of Letters Patent.

Patented Dec. 10, 1907.

Application filed September 17, 1906. Serial No. 334,870.

To all whom it may concern:

Be it known that I, BENJAMIN F. FOSS, a citizen of the United States of America, and a resident of Fairfield, Somerset county, 5 State of Maine, have invented certain new and useful Improvements in Ratchet Screw-Drivers, of which the following is a specification.

My invention relates to a ratchet screw 10 driver, wrench or other like tool and the object of the invention is to provide such a tool with means whereby an extra purchase may be obtained when an unusual amount of force is to be applied to the screw or other article 15 to be started.

According to my invention I provide a lever which is pivoted to a sleeve mounted between the handle and the ratchet mechanism, which lever may be normally 20 locked in engagement with the handle so that the tool may be used as an ordinary ratchet screw driver but when it is desired to use an extra amount of force, the lever may be unlocked and used to turn the spindle with a 25 ratchet motion.

I illustrate my invention by means of the accompanying drawings in which

Figure 1—is a part central section and part elevation of a screw driver embodying my 30 invention. Fig. 2—is an elevation of a portion of the device with the adjusting ring in section. Fig. 3—is a horizontal section on Y Y of Fig. 2. Fig. 4—is a vertical section through the adjusting ring. Fig. 5—is a section on Z Z of Fig. 2, and Fig. 6—is a section on X X of Fig. 1.

In the drawing A represents the spindle which may terminate in a screw driver blade as shown or in the jaws of a wrench or otherwise as desired. The spindle is journaled in 40 the handle E and is secured in place by a screw g. The ratchet member is fixed to the spindle and between it and the handle is provided a loose sleeve to which the operating 45 lever is pivoted.

As here shown, I secure to the spindle an annular ratchet member A having ratchet teeth on its under side and two pawl bolts b b contained in suitable recesses in the end of 50 the sleeve B engage the ratchet teeth. These pawl bolts are each formed to stop the ratchet from revolving in one direction, and each has a spiral spring b' which tends to force it outward. Each pawl bolt is retracted 55 by an offset b⁴ which extends out through a slot b⁵ formed in the sleeve, and these pro-

jections are engaged by cam slots c² on the operating ring c³ which surrounds the sleeve (Figs. 4 & 5.) These cam slots are on opposite sides of the ring and are so formed that when the ring is in a central position both pawls will be locked or engaged so that the spindle will not turn in either direction, and when it is turned in either direction, one or the other pawl will be withdrawn leaving the 65 opposite pawl engaged. Outside of the operating ring c³ and secured to it there is an annular thumb piece C corrugated to insure a hold.

A ring b² is slipped on over the end of the 70 sleeve and secured thereto with a screw and this ring abuts against the end of the operating ring c³ to hold the same in place at one end. A shoulder formed on the sleeve B holds the ring c³ in the other direction so that 75 it has no longitudinal motion. The sleeve B which fits loosely over the spindle between the handle and the fixed ratchet member a has a rearward extending ferrule b³ to which is pivoted the operating lever D and fitting 80 inside of the ferrule b³ is a ferrule e which covers the end of the handle E.

Means are provided by which the lever D may be locked in engagement with the handle E so that the sleeve B will be held from 85 turning on the ferrule e. For this purpose I form a longitudinal groove in the outer surface of the handle and into this groove the lever fits when it is turned down against the handle. Means are shown for locking the 90 lever in its closed position when not in use. For this purpose I provide a spring locking bolt f at the end of the groove, the end of the bolt engaging a notch in the end of the lever. A spiral spring f² tends to force the bolt out 95 and a thumb piece f' is provided to retract it and release the lever. A spring d in the bottom of the groove serves to start the lever out of the groove so that it can be grasped by the hand. It will thus be seen that when the 100 lever is turned down and locked in the groove, the sleeve B and the handle are locked together and become practically one member so that with the ratchet mechanism it makes an ordinary ratchet screw driver. When 105 however, the lever is unlocked and brought to the position shown in dotted lines in Fig. 1, the sleeve B is free to turn freely on the spindle and the ferrule e and the handle may be held in a fixed position and the spindle 110 turned with a ratchet motion by reciprocating the lever. The tool may thus in ordinary

work be used as a ratchet screw driver or a plain screw driver and when an extra force is to be applied the lever may be disengaged and used to provide a purchase.

5 I claim:

In a ratchet screw driver, the combination of a spindle, a ratchet member on said spindle, a handle through which the spindle passes and to which it is journaled, a ferrule 10 on said handle provided with an annular exterior shouldered portion intermediate its ends, a sleeve provided with an interior annular offset bearing surface, said sleeve fit-

ting over the ferrule to rotate thereon with the inner end of the sleeve bearing against 15 the shouldered portion of the ferrule and with the annular offset bearing surface of the sleeve engaging one end of the ferrule and the handle, pawls mounted in the sleeve to engage the ratchet member, and a lever pivoted 20 to said sleeve.

BENJAMIN F. FOSS.
